UNITED STATES PATENT OFFICE.

JOHANNES ALBRECHT, OF CANNSTADT, WÜRTEMBERG, ASSIGNOR TO OTTO HERZ, OF FRANKFORT, GERMANY.

SOLE-SEWING MACHINE.

SPECIFICATION forming part of Letters Patent No. 405,453, dated June 18, 1889.

Application filed August 17, 1888. Serial No. 283,053. (No model.) Patented in Germany October 23, 1886, No. 41,153, and in France November 23, 1886, No. 179,837.

To all whom it may concern:

Be it known that I, JOHANNES ALBRECHT, a subject of the Emperor of Germany, residing at Cannstadt, Germany, assignor to Otto Herz, of Frankfort-on-the-Main, Germany, have invented certain new and useful Improvements in Sewing-Machines, (which have been patented in Germany, October 23, 1886, No. 41,153, and in France, November 23, 1886; No. 179,837,) of which the following is a specification.

I, JOHANNES ALBRECHT, of Cannstadt, in the Kingdom of Würtemberg, German Empire, mechanic, do hereby declare the nature of this my said invention, and in what manner the same is to be carried into effect. It is particularly described in and ascertained from the following statement, and is represented in the accompanying drawings.

My invention relates to improvements in sole-sewing machines, and more especially to that class of machines which produce the double lock-stitch; and it has for its object to sew the sole onto the shoe or boot, &c., with waxed threads by means of a hook-needle and of a suitable shuttle.

These improvements are shown in the accompanying drawings, in which—

Figure 1 is a side elevation, partly in section; Fig. 2, a front elevation; and Figs. 3 to 11 are detail views of special parts hereinafter described.

The machine is put in motion from the main driving shaft a , on which a fly-wheel b and a grooved disk a' and bevel-gearing A are mounted. The end of another shaft a^2 , driven by the bevel-gearing A' , is connected by a double universal joint C to the shuttle-driving mechanism, which it actuates. The shaft a^2 rests in a bearing B and can be moved up and down by a hand-lever D , operating the vertical draw-bar d and compressing the spring d' . The needle-bar n receives its reciprocating vertical motion from the lever-arm m , which in its turn is actuated by the grooved disk a' . (See Figs. 1 and 10.) The shuttle z rotates in a case r , (see Figs. 1, 2, 3, 5, and 6,) and is operated by a driver c' , mounted on shaft a^3 . The shuttle-case r is

provided with an opening r' or cutting on its lower side, and is shoved over bearing B , Fig. 5, to which it is fastened by means of screws or in any other suitable manner. Shuttle z has its points in the same plane as its side, so that the position of shaft a^2 may be made 55 to incline with respect to needle-bar n without the lower edge of the shuttle touching the needle, which thus allows the loop of the thread to be hung up upon the shuttle-point, and thus taking it out of the hook of the 60 needle, as is shown in Figs. 7 and 8. Presser-ring h , surrounding shuttle-ring r , has its fulcrum in pin h' , Fig. 6, and is exactly guided by screws h^2 and h^3 , adjustably attached to it. These screws h^2 and h^3 penetrate 65 shuttle-ring r and rest in turn against two cams e^2 and e^3 , which, revolving with the shuttle-driver c' and shaft a^2 , push alternately against them, and thus press the ring h one time to the right and another time to the 70 left, while a spring h^4 is permanently tending to push the ring downward and a spring h^5 to the right. The downward motion is effected by the cam e^3 operating against the projection h^6 . The screw h^2 is also an adjusting-screw, serving to regulate the size of the stitches in the following manner, viz: 75 When it is screwed forward, the ring h will travel a greater distance than when the screw is screwed back. The presser-point x' is 80 screwed to case r and holds the material being sewed down upon the top of the horn P . To the presser-ring h is attached the feed-arm X , which, coming into operation alternately with the presser-point x' , follows the motion imparted to the ring h by the cams e^2 e^3 and springs, as afterward described, and thus moves the stuff forward after each stitch has been finished and as soon as the needle has moved up out of the stuff. 85

The horn P is made movable in its bearing p in the ordinary manner, projecting from the frame of the machine.

The horn P is given the shape shown in Fig. 1, in order that a high-legged boot will 95 take its proper place and can be easily guided when being sewed. This shape of the horn allows, further, that the lower thread

passes up the inside of the horn in nearly a vertical direction, by which the mechanism is very much simplified, whereas in other sewing-machines with horns known hitherto 5 the thread has had to pass a sharp angle or two.

The take-up lever K receives its reciprocating motion from the grooved drum K', which is attached to and rotated by the shaft k', and carries at its front end the vertical bar k², 10 (see Fig. 2,) which has a take-up roller u at its top end and is guided on the rod v, which latter is journaled in bearings at its top and bottom ends, and at its top end is in gearing with the rod v'. The rod v' is connected at 15 its upper end by a small universal joint with the rod v², which latter drives at its top end a whirl of the ordinary construction in the ordinary manner. The thread, starting from the spool E, passes over and is guided by the 20 rolls g, take-up roller u, and rolls g' and g² to the whirl.

The rod v is geared at its lower end with the rod V, which in its turn is geared with the rod k', from which it receives its motion, 25 and is kept in rotation as long as the machine moves. The consequence of this will be that the rods v' and v² are also rotated, causing the thread to be laid upon the hook of the needle as soon as it has passed through the work. 30 When the needle moves up again, the thread goes up with it through the work, whereupon the shuttle passes through the loop in the manner described, after which the take-up 35 pulls the loop back over the shuttle, thus producing, together with the shuttle-thread, a perfect stitch.

In the upper part of the machine is situated the bearing B, before named, which, together with the shuttle z, case r, and presser 40 x, with ring h, can be lifted by lever D, Fig. 2, as before described, and the cloth or leather passed between these parts and the horn.

During the passage of the needle up through the stuff a locking device comes into 45 operation, which holds the bearing B, with the case r and presser-point x', together with the ring h and feed-arm X, firmly down upon the work being sewed. This locking device is represented in Figs. 4 and 1. It consists 50 of the arm S and spring S', both attached at their top ends to the frame of the machine. The lower end of the arm S has a claw s, which holds in the rack s', this latter being attached to the bearing B. Below this claw s 55 is situated the projection s'' on the arm S. On the shaft a², which operates the shuttle-driver, as before described, is situated the cam b'', which is so adjusted to said shaft a² that at the moment the needle arrives at its highest point 60 and is perfectly free from the stuff the cam b'' presses against the projection s'', and thus withdraws the claw s from the rack s'. This happens at the same moment that the feeding of the work is effected. As soon as the cam b'' passes away from s'' the spring S' draws back the arm S, thus again locking down the

bearing B. The lever D is now lowered, thus bringing the presser down again upon the work, whereupon the machine is started. By these means needle f will go back and take up 70 lever K, together with thread-roll u, and move upward until the shuttle has come into the position shown in Fig. 9. In the moment the needle has arrived in position, Fig. 7, the shuttle enters the thread-loop and draws 75 along the thread as much as is necessary for its passage, whereby the thread is taken off the hook of the needle, Fig. 8. When the shuttle and the needle are in position, Fig. 9, the thread-lever K moves down and draws the 80 thread tight.

It must be mentioned that before the thread has been drawn tight cam e³ has pushed against check h⁶, and has thus pressed the presser-foot x against the cloth or sole-leather. The presser-foot x will be raised again as soon as spring c is compressed above the bearing B. Cam e² now presses against set-screw h², and so moves the material to the left. The cam e³ has now come in contact 90 with the projection h⁶, pressing down the feet-point x' into the material, whereupon the cam e² pushes against the screw h², moving the feet-point x' forward. As soon as the cams e² and e³ have ceased to act the springs 95 h⁴ and h⁵ return h to its original position. The shuttle z is held up against the front of the shuttle-case r by the spring z'. It will thus be seen that the springs and the presser, in combination with the set-screws, 100 and together with the shuttle, will adjust themselves automatically, according to the thickness of the material to be sewed. As soon as the presser has gone back the needle will make a new stitch, and all movements of 105 the operating parts will commence anew.

Having thus described my invention and the manner of employing the same, what I claim as my invention, and wish to have secured to me by Letters Patent of the United 110 States of America, is—

1. In a sole-sewing machine with a straight vertical needle, a shuttle rotating in its case in a vertical plane behind the said needle above the stuff or material being sewed, in 115 combination with the shuttle-case, the vertically-yielding bar d, carrying said case, the bearing B, and the universally-jointed shuttle-driving shaft, whereby an automatic adjustment to the thickness of the stuff is effected, substantially in the manner as described.

2. In a sole-sewing machine, the combination, with the vertically - yielding bar d, the shuttle - case r, carried thereby, and the 125 presser-foot x', attached to the shuttle-case r, of the pivoted presser-ring h, the feed-arm X, secured thereto, the shaft a², and the cams e² e³, formed thereon, all arranged substantially as shown, and for the purpose described.

3. In a sole-sewing machine, the combination, with the shaft a² and the cams e² and e³,

formed therein, of the pivoted presser-ring h , the shuttle-case r , screws h^2 and h^3 , springs h^4 and h^5 , the projection h , and the feed-arm carried by the said ring h , all arranged substantially as shown, and for the purpose described.

4. In a sole-sewing machine, the locking device consisting of the arm S , spring S' , claw s , and rack s' , in combination with the projections s^2 on the arm S , cam b^2 , attached to the

shuttle-driving shaft a^2 , bearing B , shuttle-case r , presser-point x' , together with the ring h and feed-arm X .

In testimony whereof I have signed my name to this specification in the presence of two subscribing witnesses.

JOHANNES ALBRECHT.
